Ill., a corporation of Delaware

Application November 9, 1935, Serial No. 48,977

3 Claims. (Cl. 179—18)

The present invention relates to telephone systems in general, but is concerned more particularly with automatic telephone systems. The object of the invention is the production of a novel 5 arrangement for improving the reliability of the testing operation of an automatic switch when connection is being extended to a desired called line.

The invention is concerned particularly with 10 the provision of a satisfactory solution of a problem which involves automatic connector switches already manufactured and installed. The problem is to provide a simple refining circuit arrangement which renders existing connectors 15 immune to false testing or connecting operations responsive to inadvertent or malicious unstandard control exercised over a connector from the calling line.

General description

20 The nature of the problem to be solved will be apparent from the following brief discussion:

In an automatic telephone system, it is customary to so arrange the circuit apparatus that 25 a negative potential is placed on the third or control conductor of a subscriber line by way of the individual cut-off relay thereof when the line is idle and to place a ground potential on this conductor to operate the cut-off relay when the line is in use, which ground potential is employed in a testing operation to indicate the fact 30 that the line is in use.

For several years, a standard testing arrangement has been used in connection with two-motion Strowger connector switches. This testing arrangement includes a double test, first for 35 the presence or absence of the guarding ground potential on the third or control conductor of the called line, and then for an idle-indicating battery potential in the event that the ground potential is not encountered. The sequence of 40 these two tests is controlled by a slow-acting changeover relay which is energized throughout the rotary movement of the selector. The test for the ground potential is effected by a busy 45 relay which operates and locks itself in the event that ground potential is encountered by the test wiper when the switch has come to rest, while the final test is accomplished by the usual wiper-switching relay, to the test winding of which the test wiper is transferred upon the restoration of the above-mentioned changeover relay. In the event that the called line is busy, the busy relay locks itself, as above mentioned, upon the restoration 50 of the slow-acting relay and the rotary

stepping circuit is opened by the cooperation of the busy relay and the slow-acting changeover relay so as to prevent further unnecessary advance of the wipers in the event that the calling subscriber should dial an additional digit, as well 5 as when the calling subscriber replaces his receiver.

When the called line is idle, the above-mentioned wiper switching relay is permitted to operate following the changeover operation. As is 10 necessary because of the relatively small amount of power available for the operation of the wiper-switching relay in its test circuit (over the test wiper in series with the cut-off relay of the called line), the first operation of the switching relay 15 is to close a pair of lightly adjusted locking contacts in order to produce a local energization of the relay sufficiently strong to bring about a complete operation. A short time elapses, therefore, 20 following the closure of the local locking circuit before the disconnection of the rotary magnet occurs upon the full energization of the relay. Therefore, if the calling line is momentarily interrupted an additional time and this interruption is so timed that the line relay of the connector 25 transmits an additional impulse after the locking circuit of the switching relay has been closed and before the rotary magnet has been disconnected, the connector is caused to take an additional step and the wipers of the connector are 30 advanced to the next succeeding line. Connection is made with the next succeeding line whether it is busy or idle, as the local locking circuit of the switching relay remains established. Under this condition, therefore, the connector 35 makes connection with a busy line; this is highly undesirable, for it enables the privacy of a telephone conversation to be invaded.

In addition to permitting the privacy of a conversation to be invaded, the foregoing occurrence 40 often leads to the called busy line being tied up and withheld from further service because of a locked condition which results when a connector cuts in on a busy line when the connection is reversed between the connector banks and the 45 lineswitch, as will be brought out in the detailed description which is to follow.

The additional impulse which causes the undesired operation above referred to is believed 50 to be usually transmitted by a momentary depression of the hook switch at the calling station almost immediately following the delivery of the last impulse of the final digit by the calling device. This momentary depression of the hookswitch may be inadvertent and without any 55

malicious intent on the part of the calling subscriber, or (as has been found to be the case) intentional and malicious on the part of informed groups of subscribers. One of these informed subscribers, on calling a line and finding it busy, often replaces the receiver and then removes it and again dials a number the second time setting the connector on the preceding contact group in the bank. If the line associated with the preceding contact group is idle, the switching relay starts to operate in the usual way and closes the locking circuit previously mentioned, but the additional impulse is then received and causes the wipers to be stepped to the busy line before the switching relay has operated far enough to disconnect the rotary magnet, whereby connection with the busy line is obtained, because the switching relay (having once closed its local locking circuit) operates fully regardless of any subsequent test conditions which may be encountered.

Once the problem previously set forth has been discovered and analyzed, several simple remedies may suggest themselves, such as arranging that the reoperation of the slow-acting control relay which occurs when the additional impulse is delivered shall break the locking circuit of the switching relay unless the relay has operated sufficiently to open the rotary magnet circuit. An arrangement such as this, however, involves a major wiring disturbance of the switch, as additional spring contacts must be added to the existing relay apparatus, which usually proves to be quite expensive. The invention is concerned with the production of an arrangement curing the trouble by the addition of new equipment to the connector and without making an extensive change in the existing equipment.

In the preferred embodiment of the invention, rotary off-normal contacts are provided which by a very simple wiring change cooperate with the slow-acting control relay above mentioned to open the rotary stepping circuit upon the restoration of the slow-acting control relay, and therefore before the switching relay has had time to start to operate. A modification of the invention discloses a self-locking relay which may be used in place of the rotary-off-normal contacts.

As will be pointed out hereinafter it was found necessary to provide a resistor in addition to the contacts mentioned in order to avoid interfering with a subsequent operation of the slow-acting control relay when the receiver is replaced at the calling substation after conversation.

Referring now to the accompanying drawing comprising Figs. 1 and 2, they show by means of the usual circuit diagrams a sufficient amount of the equipment in a telephone system embodying the invention to enable the invention to be understood. Fig. 1 shows the apparatus involved in a call between two lines in a typical telephone system employing a two-motion Strowger release-by-last-party connector C to which the invention has been applied, while Fig. 2 shows the invention applied in its modified form.

In Fig. 1 the substation A is a well known form of automatic substation provided with serially related transmitter and receiver, and the usual form of calling device; a lineswitch of the usual rotary type is indicated at LS1; a selector of the usual Strowger type is indicated at S; at C the circuits of a connector are shown complete with the preferred form of the invention applied

thereto; at B is shown an automatic substation similar to the substation A, and at LS2 the circuits of the lineswitch associated with substation B are shown for illustrative purposes.

In Fig. 2 the self-locking relay 51 is provided 5 in lieu of the rotary-off-normal contacts 17 of Fig. 1, as will be pointed out hereinafter.

Detailed description

The disclosure having been described in general, a detailed description of the operation of the apparatus shown will now be given. For this purpose, the regular operation of the system will be first described as it takes place without the invention applied to the connector C. Previous to the application of my novel invention thereto, the connector C is as shown, with the wire indicated by the dotted line 19 in place and with resistor 18 and rotary-off-normal contacts 17 not included. In the detailed operation 20 which is to follow, it will be assumed that the parts 17 and 18 are not applied to the connector C and that the wire 19 is in its normal position as indicated in the drawing.

A call from substation A to substation B

Assuming now that the subscriber at substation A desires to converse with the subscriber at substation B the subscriber at substation A removes his receiver and then dials the digits of 30 the desired number. With the system as herein indicated (there being one selector and a connector in the switch train) a three-digit number is used.

When the receiver is removed at substation A, 35 the lineswitch LS1 operates in the usual manner to select an idle trunk extending to a first selector, the one extending to the selector S, for example.

When the first digit is dialled, the selector S 40 raises its wipers opposite the desired level and then rotates them over the contacts in this level in search of an idle connector. It may be assumed that the connector C is the first one found to be idle, in which case this connector is 45 seized by the selector S.

When the connector C is seized, line relay 6 is energized over the calling line by way of the normally closed contacts controlled by armatures of the back-bridge relay 8. Upon energizing, line 50 relay 6 operates release relay 7 to prepare the selector for operation, which includes the placing of ground potential on the local locking conductor 32 and the application of ground potential to release trunk conductor 3 in order to provide a 55 holding circuit for the selector S and the lineswitch LS1.

When the calling subscriber dials the second digit in the desired number, each resulting de-energization of line relay 6 results in the momentary opening of the circuit of slow-acting release relay 7 and in the closure of a circuit for vertical magnet 18 by way of vertical series relay 8 through the inner lower armature of the operated relay 7. Vertical series relay 8 operates and makes a circuit transfer in order to maintain its own circuit and that of vertical magnet 18 intact after the off-normal springs 16 have shifted, as they do upon the first vertical step of the switch. By the operation of the vertical magnet, the wipers 20-22 of the connector C are raised opposite the desired level of bank contacts, the level in which the line of sub-station B terminates.

At the end of the vertical movement, vertical 75

series relay 8 restores and transfers the operating circuit to rotary magnet 14 through contacts of busy relay 10 and the middle lower armature and resting contact of switching relay 12.

5 When the final digit is dialled, each resulting impulse from the contacts of line relay 6 is transmitted to rotary magnet 14. By the operation of magnet 14 the wipers 20-22 of the connector are rotated step-by-step until they come into engagement with the terminals assigned to the line of the desired substation, B. The slow-acting rotary-series relay 11 is energized in multiple with rotary magnet 14 and remains energized throughout the series of impulses delivered to the rotary magnet. At its upper armature, rotary-series relay 11 disconnects test wiper 21 from the test winding of switching relay 12 and transfers it through contacts of relay 12 to the busy-test relay 10, while at its lower armature it places a shunt around the lower armature and resting contact of relay 10 so as to maintain the circuit of the rotary magnet and its own circuit intact against an opening thereof by busy relay 10 occasioned by energization of the busy relay responsive to test wiper 21 encountering grounded test contacts during the rotary movement.

The operations taking place at the end of the rotary movement depend upon whether the called line is busy or idle. If the called line is busy, busy relay 10 is in an energized condition when the wipers come to rest on the terminals of the called line, as test wiper 21 then encounters a grounded test contact. In this event, busy relay 10 has prepared a self-locking circuit, which is completed when rotary-series relay 11 restores upon the cessation of impulses. With relay 11 restored and relay 10 in operated condition the test circuit through the upper winding of relay 12 is opened at the upper contacts of relay 10; the rotary magnet circuit is opened at the inner lower armature of busy relay 10 and the lower contacts of the now-restored rotary-series relay 11; and a busy-tone signal from busy-tone lead 45 is transmitted back over the lower talking conductor to the calling subscriber to inform him that the called line is busy. The calling subscriber is expected to replace his receiver and permit relays 6 and 7 to restore pursuant to the restoration of the connector C and the clearing out of the partly established connection.

Assuming now that the line of substation B is idle when called, busy relay 10 is not in an energized condition when the wipers come to rest on the terminals of the called line. In this event, the rotary-magnet circuit is still unopened when rotary series relay 11 restores upon the cessation of impulses, and a test circuit is completed from the grounded incoming release-trunk conductor 2 to test wiper 21 by way of the upper winding of switching relay 12, which test circuit includes the upper contacts of relays 10 and 11. The upper winding of switching relay 12 is now energized in a circuit which includes wiper 21, the switching relay 46 of the lineswitch LS2, and the winding of the operating magnet 48. Relays 12 and 46 are energized in this circuit, but, as is well known, magnet 48 is not operatively energized. Relay 46 operates to disconnect the windings of line relay 46 and ground from the talking conductors of the called line, but the relay is not completely operated to connect up the wipers because of the usual interlocking arrangement (not shown) between the armature of relay 46 and the armature of relay 47.

75 In the connector C, when relay 12 is partially

energized by means of its upper winding, it first closes a local locking circuit for itself at its inner lower contacts to complete its energization whereupon it operates the remaining armatures as a result of the energy supplied to the relay in the local locking circuit of the lower winding. Upon operating fully, relay 12 disconnects rotary magnet 14; applies ground potential directly to test wiper 21; disconnects busy test relay 10, connects up the wipers 20 and 22 to prepare the talking circuit and close the ringing circuit; and it applies ground potential by way of contacts of ring-cut-off relay 23 to the motor-start conductor 43 so as to start the ringing apparatus (not shown) into operation.

Ringing current from the interrupted-generator lead 44, superimposed upon ground potential, is now applied through the lower contacts of relays 9 and 12 and one conductor of the called line. As is well known, relay 9 is so retarded in action that it does not respond to the flow of ringing current in the event that bridged ringing is employed, and direct current is prevented from flowing by the usual condenser in series with the ringer at the called substation.

When the called subscriber removes his receiver to answer the call, relay 9 operates by means of its upper winding and closes a locking circuit for itself at its inner lower armature to conductor 32, grounded at the lower armature of release relay 7. Relay 9 also opens the ringing circuit and completes the talking circuit.

At this point, back-bridge relay 5 energizes over the called line, a ground connection having been applied to its lower winding by the closure of the locking circuit of the lower winding of relay 9 from grounded conductor 32. Upon energizing, back-bridge relay 5 reverses the connections between the incoming talking conductors 2 and 4 and the windings of line relay 6 so as to provide a reversal of current flow in the calling line for whatever purpose desired. Back-bridge relay 5 also disconnects ground potential from supervisory-one conductor 42 at its lower armature, which ground potential is applied upon the operation of ring-cut-off relay 9. At the same lower armature of back-bridge relay 5, a new source of ground potential is applied to conductor 32 so as to maintain relays 9 and 12 locked independent of the continued operation of release relay 7, this feature having to do with the last-party-release operation of the connector C, to be subsequently explained. Backbridge relay 5 also opens an additional point in the circuit of release magnet 15, also having to do with the last-party-release operation, and prepares to apply ground potential to supervisory-two conductor 41 upon the restoration of relays 6 and 7.

Conversation may now proceed as desired. In the event that the called subscriber is the first to replace his receiver, the restoration of the back-bridge relay 5 results in the extension of ground potential at the lower armature to supervisory-one lead 42, which may be utilized by a slow-acting signal device common to a group of connectors to indicate that a connector is being held from the calling line after the called subscriber has replaced his receiver. The connector is not released, because release relay 7 remains operated.

On the other hand, in the event that the calling subscriber is the first to replace his receiver, the deenergization of line relay 6 is followed by the restoration of release relay 7. Rotary magnet 75

14 is not operated at this time during the interval required for release relay 7 to restore after its circuit is opened by relay 6, as the rotary magnet has been disconnected at the contacts of switching relay 12. Rotary series relay 11, however, has not been disconnected as it is now restored to perform an additional operation. When relay 11 operates, it again makes a transfer of test wiper 21 from the winding of relay 12 to the contacts associated with the windings of busy relay 10, but busy relay 10 is not operated at this time as it has been disconnected at the inner upper contacts of switching relay 12 to prevent its operation under the condition now obtaining. 10

15 The operation of relay 11 at this point serves merely to disconnect the incoming release trunk conductor 3 from test wiper 21, now grounded at the middle upper armature of relay 12, whereby the incoming release trunk conductor 3 becomes 20 completely ungrounded upon the restoration of release relay 7.

At this point, the selector S is permitted to release and the lineswitch LS1 is permitted to clear out.

25 The restoration of release relay 7 does not result in the ungrounding of conductor 32 and the consequent restoration of relays 9 to 12 because conductor 32 is now maintained grounded through operated contacts of relays 12, 9, and 5. 30 When relay 7 restores, it opens the operating circuit extending to rotary series relay 11, permitting this relay to restore after a slight interval, whereupon ground potential is reapplied to the incoming release-trunk conductor 3 from the 35 grounded test wiper 21 (grounded at the middle upper armature of relay 12). This ground connection includes the upper contacts of relays 11 and 10, and the upper winding of switching relay 12. The resistance of the upper winding of relay 12 is sufficiently low to cause test conductor 3 to test busy to any selector (such as S) which subsequently rotates over the contacts of the connector C. The connector C is thus maintained 40 guarded against further seizure as long as it is held operated from the called line.

45 Upon the restoration of relay 7, back-bridge relay 5 being still in an operated condition, ground potential is applied to supervisory-two conductor 41, by means of which a signal common to a group of connectors may indicate that 50 a connector is being held from the called line after the calling subscriber has replaced his receiver.

55 It may be explained that the holding of the connector C from the called line at this time prevents a needless operation of the lineswitch LS2 which would otherwise take place in the event that the calling subscriber is the first to replace his receiver, and a first selector would 60 be needlessly taken into use and again released when the subscriber at substation B replaces his receiver. The arrangement disclosed is one that has been in use for many years and its use is based on the theory that it is better to retain in use the switch which has already been occupied than it is to permit the lineswitch on the called line to search for and take another switch into use.

70 When the called subscriber now replaces his receiver, the restoration of back-bridge relay 5 results in the removal of ground potential from conductor 32, thereby opening the locking circuit of relays 10 and 12 to permit these relays to restore. Ground potential is also removed 75 from supervisory-two conductor 41, and the cir-

cuit of release magnet 13 is closed by way of contacts in the vertical-off-normal spring-combination 16. By the operation of release magnet 15, the connector C is restored to normal position, whereupon the release-magnet circuit is 10 opened at the off-normal contacts. The connector C becomes unguarded as soon as ground potential is removed from the incoming release-trunk conductor at the middle upper armature of switching relay 12. 10

Unstandard operation of the connector C

The regular intended operation of the connector C having been described, it will be pointed out how the unstandard and undesirable operation of the connector C may take place in the event that the calling line is momentarily opened first as the switching relay 12 is in the process of operating responsive to a successful test of an idle called line. 20

It will be recalled that when the called line is idle, the busy test, which is performed with rotary series relay 11 still energized, is terminated upon the restoration of relay 11 and that the idle test is applied by the upper winding 25 of relay 12 in the event that relay 10 has not energized to open the circuit of the upper winding of relay 12. It will be recalled also that the first operation performed by switching relay 12 is, of necessity, the closing of the local locking 30 circuit at the inner lower contacts of the relay in order to supply sufficient power for the complete operation of the relay. Now, as is well known, a measurable length of time is consumed in the operation of a relay following the closure 35 of a local locking circuit therefor. Therefore, in the event that the calling line is momentarily interrupted at about the time the locking circuit of relay 12 is closed, an additional impulse is delivered before rotary magnet 14 is disconnected 40 at the contacts of relay 12, and the wipers 20—22 are advanced an additional step. Relay 11 is operated by this additional impulse to open the circuit of the test winding of relay 12, and to again close a circuit for busy relay 10. The local locking circuit for switching relay 12, however, 45 is not affected and the relay completes its operation. Busy relay 10 is disconnected at the contacts of relay 12, as it must be in order to prevent its undesired operation in the event that the called subscriber is the first to replace his receiver following conversation. Relay 11 is shortly 50 restored after the termination of the impulse. With relay 12 completely operated, the ringing circuit is completed to the newly contacted line. 55 If this line is idle, the subscriber thereon is signalled in the usual manner. On the other hand, if the newly contacted line is busy the talking bridge across the conductors serves as an operating path for ring-cut-off relay 9, and this relay operates immediately to complete the talking 60 circuit to the busy line.

In many installations of connectors such as is indicated in Fig. 1, the conductors leading from the banks of a part of the connectors to the called lines are reversed, having to do with the giving of two-party terminal-per-station, party-line service. The conductors referred to are commonly called normal conductors. The normal conductors by which the line of substation B is reached from the connector C are shown reversed in order to illustrate an especially undesirable feature that results from the described unstandard operation of the connector C. When the line of substation B is in use as a result of 75

a call having been originated from this line, the lineswitch LS2 is then operated to set up a connection by way of a first selector and through another connector such as C. The reversed condition of the normal conductors associated with the line of substation B results in a locking circuit being closed through the back-bridge relay 5 in series with the windings of the connector in use in the call which was previously originated from the line of substation B. In this case, the established connection is not cleared out when the parties thereto replace their receivers, and the connector C is tied up and withheld from service, as is substation B and the entire switch train used to establish the connection from the line of substation B to the line which was called therefrom. This condition is, of course, eventually discovered by means of the signals controlled over the supervisory leads 41 and 42, but it is very often not discovered until the subscribers involved have been annoyed considerably, both by the intrusion upon the privacy of their conversation and the resulting tying up of their lines which follow.

25

The improved connector

The remedial measures which have been taken to remove the described defect from the connector C will now be explained. The remedying of the defect consists in cutting the wire 19, indicated by a dotted line; in connecting the resistor 18 as shown; and in applying rotary-off-normal contacts 17 to the mechanical structure of the switch and connecting them in circuit as shown. The rotary-off-normal contacts 17 may be of any well-known or desired mechanical structure such as is often used in connection with Strowger automatic switches. The only requirement is that they open when the wipers of the switch are given their initial rotary step and remain open until the wipers of the switch have been released. They are customarily operated by a longitudinal cam device gripped around the shaft of the switch and with which the insulated part of the leading spring of the combination 17 is normally in contact.

With the connector C modified as shown in the drawing, as soon as the rotary movement has started and rotary-off-normal contacts 17 have opened, the continued closure of the circuit for rotary magnet 14 depends solely upon the continued energization of rotary series relay 11. Therefore, whether the called line is busy or idle, as soon as relay 11 falls back, the rotary magnet circuit is opened (conductor 19 having been removed) for the rotary-off-normal contacts 17 are in an open condition. The current which can flow through the resistor 18 is insufficient to operate rotary magnet 14, as this resistor is applied merely for the purpose of permitting rotary series relay 11 to be reoperated when the calling subscriber is the first to replace his receiver, as previously pointed out. At such time, rotary magnet 14 has been disconnected from in circuit with rotary series relay 11 at contacts of switching relay 12, and the current which flows through resistor 18 is sufficient to operate rotary series relay 11 when it is not shunted by the relatively low resistance rotary magnet 14.

When the line called by the modified connector C is busy, busy relay 10 is in operated condition and the resistor 18 is disconnected completely as there is no occasion under this condition for providing what may be termed a leakage path for the operation of relay 7 after magnet 14 has been

disconnected from in circuit therewith. It will be understood, of course, that advantage is taken of the inner lower contacts of busy relay 10 because they happen to be already provided on the busy relay and that the circuit operation would be substantially the same if resistor 18 and rotary off-normal contact 17 were bridged directly around the inner lower contacts of rotary series relay 11 instead of by way of the inner lower armature and resting contact of busy relay 10.

5

10

The modification of Fig. 2

The modified arrangement shown in Fig. 2 will now be explained briefly. The relay 51 and the contacts shown to left thereof are provided instead of the rotary off-normal contacts 17 for use where the switch structure is such as to make it difficult to apply rotary off-normal contacts.

Relay 51 is normally connected between impulse conductor 33 and the ungrounded pole of the exchange battery, whereby it operates upon the receipt of the first rotary impulse and closes a locking circuit for itself to conductor 32 so that it remains operated thereafter. The relay also opens its initial circuit when the locking circuit is closed. At its right-hand contacts, relay 51 opens the initial circuit of the rotary magnet and rotary series relay 11, whereby the continued closure of the rotary magnet circuit depends upon the continued energization of rotary series relay 11, as explained in connection with Fig. 1. The resistor 18 has the same function in Fig. 2 as it has when applied in connection with the rotary off-normal contacts 17 in Fig. 1. Relay 51, as shown has a copper collar on the armature end thereof to render it sufficiently slow-operating to permit relay 11 to operate first.

What is claimed is:

1. In a two-motion connector switch, an operating conductor, a vertical magnet and a rotary magnet, means for delivering impulses over said operating conductor to the vertical magnet to impart the desired vertical movement to the connector, means effective for transferring the operating conductor from the vertical magnet to the rotary magnet at the end of the vertical movement, a pair of contacts included in circuit with the rotary magnet and means for opening them at the beginning of the rotary movement, a slow-acting relay and means for operating it for the duration of the series of impulses transmitted to the rotary magnet, and contacts on the slow-acting relay in multiple with the first-named contacts, whereby the rotary magnet circuit is maintained intact after the first-named contacts separate and is broken when the slow-acting relay restores upon the cessation of the rotary impulses.

2. In a vertical-and-rotary connector switch, a rotary magnet for imparting rotary motion to the connector switch after it has been operated in its vertical motion, an operating lead extending to the rotary magnet for enabling it to be operated by impulses, a self-locking relay associated with the rotary-magnet-operating lead and arranged to operate responsive to the first rotary impulse and remain locked thereafter, a slow-acting relay associated with the said lead and arranged to respond throughout a series of impulses and restore at the end thereof, and contacts on the two relays connected in parallel relationship, the contacts on the self-locking relay being normally closed and the contacts on the slow-acting relay being normally open, whereby the two relays cooperate to open the

15

30

35

75

rotary magnet circuit upon the cessation of the series of impulses.

3. In an automatic connector switch having means to drive its wipers over the terminals of lines responsive to directive impulses, means connected to the test wiper of the connector during

the driving operation for testing encountered lines, means effective upon the termination of the driving operation for disconnecting the said testing means, and means simultaneously effective for disabling the driving means.
